UNITED STATES PATENT OFFICE.

JOSEPH W. KENNA, OF CHICAGO, ILLINOIS.

DESIGN FOR A SPRING-ROCKER BRACKET.

SPECIFICATION forming part of Design No. 15.073, dated June 17, 1884.

Application filed April 22, 1884. Term of patent 3½ years.

To all whom it may concern:

Be it known that I, JOSEPH W. KENNA, residing at Chicago, in the county of Cook and State of Illinois, have invented and produced 5 a new and original Design for a Spring-Rocker Bracket, of which the following is a specification, reference being had to the accompanying drawings, forming part thereof.

Figure 1 is a view in front elevation illustrative of my design. Fig. 2 is a plan view thereof. Fig. 3 is a side elevation, these several views being deemed necessary to fully illustrate my design.

My purpose is to impart to the bracket of a 10 stationary-base-rocking-chair spring an ornamental appearance attractive to the eye and of pleasing form or outline; and to this end my invention consists more particularly in imparting to the bracket-plates thereof, or, rather, 15 the upper portions of the same, the configuration of a double eagle. In the accompanying drawings are represented the spring bracket-plates B, these plates having raised thereon 20 the figure of a double-headed eagle with its 25 wings extended as in act of flying.

Minor changes may be made in the appearance of the bracket-plates--as, for example, by increasing or diminishing the number of pinions shown on the distended wing, or by like differences in length of said pinions, or 30 by modifying the angular direction of the heads with relation to each other; but so long as the general configuration remains substantially the same to the eye of the ordinary observer I deem these alterations in detail to be within 35 the scope and spirit of my invention.

What I claim is--

The design for a spring-rocker bracket shown, consisting of the bracket-plate B, having the configuration of a double-headed eagle 40 with its wings extended.

In testimony whereof, witness my hand this 24th day of April, A. D. 1884.

JOSEPH W. KENNA.
